LOOSE LEAF BINDER

Paul O. Unger, Glen Ellyn, Ill., assignor to
 Wilson-Jones Company, Chicago, Ill., a corpor-
 ration of Massachusetts

Application August 11, 1934, Serial No. 739,401

3 Claims. (Cl. 129—13)

This invention relates to a loose leaf binder, and more particularly to a heavy duty binder of the post binder type.

It is an object of this invention to provide simple, inexpensive and efficient means for supporting the free ends of the sheet holding posts of a loose leaf binder, so that the posts will not sag when subjected to heavy loads, without interfering with the normal operation of the binder. Other objects of this invention will become apparent upon reading the following description taken in conjunction with the accompanying drawing, in which

Figure 1 is a perspective view of a loose leaf binder embodying the invention, with the covers removed and with the sheets broken away to facilitate illustration of the invention;

Figure 2 is a fragmentary top plan view of the structure of Figure 1 with parts broken away;

Figure 3 is a cross sectional view of the post structure of Figure 1; and

Figure 4 is a detail perspective view of the supporting bracket and the end of the post to which it is adapted to be secured.

In the drawing the reference numerals 2 and 3 indicate a pair of telescoping back sections. The edges of the sections are bent over, as indicated at 4 and 5, respectively, to form smooth, rigid edge extremities. The folded edges 5 fit within the edges 4 so that the two back sections may readily slide transversely relative to each other. It will be understood that any suitable binding material may be secured to the binder in any desired manner to form covers and to cover the metal back members.

The back section 2 is provided with a flange 6 to which is secured one or more conventional tubular posts 7 having a split free end. A screw 8 holds a conical wedge 9 (Figure 3) in the mouth of the tubular post 7. The wedge member 9 is hollow, and is threaded on its interior surface to receive the thread of the screw 8. Tightening movement of the screw 8 pulls the wedge 9 up into the post to expand the split end 45 of the post when it is desired to hold the back sections against expansion. A transfer bar 10 provided with any desired number of posts 11 may be inserted over the posts 7.

The back section 3 is provided with a flange 50 12 similar to the flange 6. The flange 12 carries a plurality of sheet aligning posts 13 similar to the posts 11 and is provided with a tubular post 14 registering with each post 7. The post 14 is of slightly larger diameter than the post 7 and is adapted to have the post 7 telescope therein.

A supporting bracket 15 has two outwardly extending flanges 16 permanently secured to the back section 3 by rivets 17, or in any other suitable manner. The bracket is provided with an 5 upwardly portion 18 adapted to be permanently secured to the free end of the tubular post 14 in any suitable manner to form a rigid support for the end of the post.

The upwardly portion 18 of the supporting bracket is sufficiently narrow that a plurality of 10 sheets 19 provided with conventional slotted holes 20 may be impaled on the posts 14 without any difficulty. The structure described is also suitable for use in connection with sheets provided with wide notches, instead of slotted holes. 15 in registration with the posts 14, because the posts 14 help support sheets of this type when the binder lies on its back, and the posts will be forced out of alignment unless they are provided with supporting means.

In the preferred form, as illustrated in Figure 4, the portion 18 is notched at the lower half of its outer edge, to form a projection 21. The depth of the cut away portion is preferably the same as the thickness of the tubular post 14. The upper edge of the tubular post 14 is notched, as indicated at 22, to permit the projection 21 to fit snugly therein. The outer edge of the post 14 and the projection 21 are integrally united in any suitable manner, such 30 as brazing or welding.

If desired, the notch in the portion 18 and the edge of the post 14 may be eliminated and the portion 18 secured to the post 14 in any suitable manner, or even left unsecured. However, the preferred form described above provides a more satisfactory structure because of the rigid, positive support it provides. A slot or aperture of any desired shape might be substituted for the notch 22. In this event, the upwardly portion 18 of the supporting bracket would be provided with a suitably shaped projection to replace the projection 21.

Although I have described only one preferred embodiment of my invention in detail, it will be understood that various changes and modifications might be made without departing from the spirit or scope of my invention. Accordingly, I do not desire to be restricted to the exact details of construction described, except as limited 45 by the appended claims.

I claim:

1. In a loose leaf binder, a sheet impaling post notched at one end, and a supporting bracket comprising an upwardly portion and a flange 55

- extending at right angles thereto, said upstanding portion having a projection fitting into said notch, said supporting bracket being permanently secured to said post.
- 5 2. In a loose leaf binder, a back section, a flange extending at right angles to said back section, a sheet impaling post having one end permanently secured to said flange and the other end notched, and a supporting bracket secured to said back section and having a projection fitting into said notch, said projection being permanently secured to said post.
- 10 3. In a loose leaf binder, a hollow sheet impaling post having a notch extending through the wall of the post at one end thereof, and a supporting bracket comprising an upstanding portion and a flange extending at right angles thereto, said upstanding portion having a projection fitting into said notch, said projection terminating substantially flush with the inner surface of the wall through which it projects and permanently secured thereto. 5 10

PAUL O. UNGER.
